Attorney

UNITED STATES PATENT OFFICE.

JOSEPH D. HARRIS, OF DETROIT, MICHIGAN, ASSIGNOR TO McCORD RADIATOR & MFG. CO., OF DETROIT, MICHIGAN, A CORPORATION OF MAINE.

RADIATOR CORE.

Application filed June 27, 1925. Serial No. 40,111.

The main object of my invention is to provide flat spacer or division plates in the air passages of a radiator core with truss-like projections and V-shaped wings struck out 5 from the plates and projecting into the air passages to increase the turbulence of the air in passing through the core and thus effect better cooling by turning the colder portions of the air against the heated metal.

10 The invention consists further in the matters hereinafter described and claimed.

In the accompanying drawings—

Fig. 1 is a front elevational view of a 15 radiator having a core embodying the features of my invention;

Fig. 2 is an enlarged fragmentary front elevational view of a detail of core structure to be hereinafter described;

Fig. 3 is a transverse sectional view taken 20 on line 3—3 of Fig. 2;

Fig. 4 is a vertical sectional view taken on line 4—4 of Fig. 3, with the outermost plates of the water passages and spacing strips omitted for the sake of illustration;

25 Figs. 5 and 6 are perspective views of the spacer plate looking at the opposite sides thereof, respectively; and

Fig. 7 is an elevational view of a detail 30 of construction to be hereinafter described.

The radiator, as indicated in Fig. 1, has an outer casing or shell 1, containing a core 2 embodying the features of my invention. The core is of the cellular type and has upper and lower tanks and a plurality of pairs 35 of corrugated sheet metal plates 3, 4 extending vertically between the tanks and so made and arranged to form zigzag water passages 5, 5 alternated by air passages 6, 6, as in structures of this general character.

40 The plates 3, 4 of each pair are oppositely disposed and are arranged to have their corrugations extend into each other, with the corrugated marginal portions of the plates along their longitudinal edges offset and interfitting to space apart the remaining intermediate portions of the plates to provide water passages between them, as shown in Fig. 3. In practice, the plates 3, 4 of each pair are integrally joined at one end by making 45 the plates from a single piece of sheet metal ribbon stock and folding it on itself intermediate its ends after being corrugated to bring the plates into the relation shown,

The several pairs of plates 3, 4 are spaced apart to provide the air passages 6, 6 by corrugated strips 7, 7 between and along the longitudinal edges of these plates, as shown. The corrugations of these strips 7 conform to the shape of the corrugations of the plates 3, 4 and, when made on hexagonal lines as shown in the drawings, give the front and rear faces of the core a honeycomb appearance. The strips 7 are integrally connected with their respective plates at spaced intervals in the length thereof and are folded over on the same in the making, as in the Erickson Patent No. 1,233,765, granted July 17, 1917.

A vertically disposed flat sheet metal spacer or division plate 8, made in accordance with my invention, is placed in each air passage 6 between the plates 3, 4 forming the same. This plate 8 is narrower than the depth of the core and lies between the strips 7, 7, the latter holding the plate from displacement from front to rear of the core, as shown in Fig. 3.

Each plate 8 is provided with a plurality of truss-like projections 9, 9 preferably arranged in rows lengthwise of the plate and on the same side thereof, as shown in Figs. 5 and 6. Said projections 9 are preferably formed by shearing the plate 8 along the lengths of the projections at the opposite sides thereof and then pressing the same out of the body of the plate to one side and shaping the projections to have flat mid-portions 10, 10 and inclined end portions 11, 11.

The plate 8 is placed in the air passage 90 between its associated plates 3, 4 with the projections 9 extending into the corrugations of the plate 4 on the side of the projections and with the inclined end portions 11, 11 of the projections in surface contact with the inclined side walls of said corrugations, as shown in Figs. 2 and 4. Thus in assembling the core, the projections 9, 9 readily find their way into the corrugations of the associated plates 4 and act to center the 95 plates 8 in proper relation with their associated plates 3, 4.

The projections 9, 9 hold the opposite side of the plate 8 against the adjacent portions of the corrugations of the plate 3, said plate 100 3 having the crowns of its corrugations

flattened, as at 12 in Fig. 4, so that relatively wide contact may be had between these plates for increased heat transference from plate 3 to plate 8.

5 The projections 9, 9 are vertically disposed and are arranged edgewise to the general direction of the air currents passing through the core, so as to split the air currents and create air turbulence for turning 10 the colder air against the heated metal to effect better cooling.

The plate 8 is also provided with a plurality of outwardly projecting wings 13, 13 struck out from the plate on opposite sides 15 thereof, as shown. These wings are struck out from the metal of the plate and are made V-shape in form as shown, so as to facilitate manufacture of the same. By having the wings V-shape, they present inclined surfaces 20 to the air currents passing through the core, and thus serve to increase air turbulence by splitting the air currents and turning the colder portions thereof against the heated metal. In punching out the projections 9 25 and also the wings 13, openings are provided in the plate at the projections and wings, respectively, so as to allow air currents to pass through the plate and reach the heated metal on opposite sides thereof in 30 addition to creating cross-currents to further increase air turbulence and thus provide for more efficient cooling.

As shown in Figs. 5 and 6, the projections 9 and wings 13 are arranged in rows lengthwise of the plate 8, with the projections 9 of one row staggered with respect to the projections 9 of an adjacent row. The plate has two rows of wings 13 between the two rows of projections 9, and these wings extend outward from the side of the plate 8 opposite the projections 9. There is also a row of wings 13 between each longitudinal edge of the plate and the adjacent row of projections 9. There is also a row of wings 13 in line 45 with a row of projections 9, with the wings and projections alternating as shown. These wings extend out from the plate from the same side as the projections 9. Moreover, these wings are laterally alined with the projections 9 of the opposite row, while the other projections are laterally alined so at 50 least one of the projections is adjacent the same.

As shown in Fig. 4, the wings 13 project 55 into the corrugations of the adjacent plates 3, 4 and are disposed edgewise to the general direction of the air currents passing through the core for splitting the air currents to increase air turbulence. Moreover, it will be 60 observed in Fig. 2 that certain of the wings 13 are directly opposite the flattened portions 12 of the plate 3 and extend outward therefrom toward the plate 4 with the openings made in the plates by these wings at the flattened 55 portions. This of course allows the

air to reach the flattened portions behind the wings to aid in cooling the radiator core.

The details of structure shown and described may be variously changed and modified without departing from the spirit and 70 scope of my invention.

As shown in Figs. 2 and 3, the mid-portions 10, 10 extend across or bridge the corrugations in which they are located to split the air currents passing therethrough. The 75 projections and wings provide increased metal surfaces for contact with said currents to provide for better cooling. The plates 3, 4 in their corrugations have bulged portions 14, 14, and 15, the latter being larger than the 80 first two and between the same, to interrupt the air currents passing through the core to increase air turbulence. After being assembled, solder is applied to the front and rear surfaces along the edges of the strips 85 and plates to close the joints along the water passages and to also connect the parts together.

I claim as my invention:

1. In a radiator core, the combination with 90 two spaced apart corrugated plates, of a flat spacer plate between the corrugated plates and having a plurality of truss-like projections extending into the corrugations of one of the corrugated plates and in contact therewith for holding the spacer plate against the other corrugated plate, the latter having the crowns of its projections flattened to increase the area of contact with the spacer plate, said spacer plate being provided with 100 a plurality of V-shaped projections struck out therefrom and with the openings made in the plate by certain of the projections opposite said flattened portions.

2. In a radiator core, the combination with 105 two spaced apart corrugated plates, of a flat spacer plate between the corrugated plates and having a multiplicity of truss-like projections struck out from one side of the spacer plate and extending into the corrugations of one of the corrugated plates and in contact with the inclined portions thereof for holding the flat body portion of the spacer plate against the crowns of the corrugations of the other corrugated plate, said 110 spacer plate being provided in its flat body portion with a multiplicity of outwardly projecting V-shaped wings struck out therefrom and distributed thereover, said wings being relatively smaller than the truss-like 115 projections and disposed opposite the depressions in the corrugated plates.

3. In a radiator core, the combination with 120 two spaced apart corrugated plates, of a flat spacer plate between the corrugated plates and having a multiplicity of truss-like projections struck out from one side of the spacer plate and extending into the corrugations of one of the corrugated plates and in contact with the inclined portions thereof, 125

• said projections having portions bridging the corrugations of the last named corrugated plate for holding the flat body portion of the spacer plate against the crowns of the corrugations of the other corrugated plate, said spacer plate being provided in the flat body portion thereof with a multiplicity of V-shaped wings struck out therefrom and

distributed thereover and arranged opposite the depressions in the corrugated plates, said 10 wings being relatively smaller than the truss-like projections.

In testimony whereof I affix my signature this 4 day of June, 1925.

JOSEPH D. HARRIS.
